[57] CLAIM

The ornamental design for a position indicator, as
shown.

DESCRIPTION

FIG. 1 is a perspective view of a position indicator
showing my new design;

FIG. 2 is a side elevational view thereof;

FIG. 3 is a top plan view thereof, with the bottom plan
view being identical thereto;

FIG. 4 is a front elevational view thereof; and

FIG. 5 is a rear elevational view thereof.
